UNITED STATES PATENT OFFICE

CHARLES S. GAGE, OF TARRYTOWN, NEW YORK, ASSIGNOR TO LENTHERIC INCORPORATED OF NEW YORK CITY, OF NEW YORK, N. Y., A CORPORATION OF NEW YORK

DESIGN FOR A LIP STICK CASE

Application filed April 21, 1933. Serial No. 47,855. Term of patent 14 years.

To all whom it may concern:

Be it known that I, CHARLES S. GAGE, a citizen of the United States, residing at 300 South Broadway, Tarrytown, New York, have invented a new, original, and ornamental Design for a Lip Stick Case, of which the following is a specification, reference being had to the accompanying drawing, forming a part thereof.

In the drawing:

I claim:

The ornamental design for a lip stick case substantially as shown.

CHARLES S. GAGE.
